(57) **CLAIM**

I claim the foldably constructed reinforceable pallet bottom, as shown and described.

DESCRIPTION

FIG. 1 is an isometric view of a first embodiment of a foldably constructed reinforceable pallet bottom connected

to a pallet top for illustration purposes. The pallet top is shown in dashed lines for environment.

FIG. 2 is an isometric view of the foldably constructed reinforceable pallet bottom of FIG. 1 with the pallet top removed.

FIG. 3 is a top plan view of the foldably constructed reinforceable pallet bottom of FIG. 2.

FIG. 4 is a bottom plan view of the foldably constructed reinforceable pallet bottom of FIG. 2.

FIG. 5 is a front elevation view of the foldably constructed reinforceable pallet bottom of FIG. 2.

FIG. 6 is a rear elevation view of the foldably constructed reinforceable pallet bottom of FIG. 2.

FIG. 7 is a left side elevation view of the foldably constructed reinforceable pallet bottom of FIG. 2.

FIG. 8 is a right side elevation view of the foldably constructed reinforceable pallet bottom of FIG. 2.

FIG. 9 is an isometric view of a second embodiment of a foldably constructed reinforceable pallet bottom connected to a pallet top for illustration purposes. The pallet top is shown in dashed lines for environment.

FIG. 10 is an isometric view of the foldably constructed reinforceable pallet bottom of FIG. 9 with the pallet top removed.

FIG. 11 is a top plan view of the foldably constructed reinforceable pallet bottom of FIG. 10.

FIG. 12 is a bottom plan view of the foldably constructed reinforceable pallet bottom of FIG. 10.

FIG. 13 is a front elevation view of the foldably constructed reinforceable pallet bottom of FIG. 10.

FIG. 14 is a rear elevation view of the foldably constructed reinforceable pallet bottom of FIG. 10.

FIG. 15 is a left side elevation view of the foldably constructed reinforceable pallet bottom of FIG. 10; and, FIG. 16 is a right side elevation view of the foldably constructed reinforceable pallet bottom of FIG. 10.

The dashed lines in FIGS. 1 and 9 illustrate a pallet top for environment and form no part of the claimed design. The dashed lines in FIGS. 2 and 3 illustrate portions of the foldably constructed reinforceable pallet bottom that form no part of the claimed design.

1 Claim, 12 Drawing Sheets
